DIAPHRAGM FOR PHONOGRAPHIC REPRODUCERS.

Application filed March 25, 1925. Serial No. 18,232.

The invention relates to improvements in diaphragms for phonographic reproducers as described in the present specification and shown in the accompanying drawings which 5 form part of the same.

The invention has for its object to provide a phonographic diaphragm possessing certain features resulting in the better and more natural reproduction of sound, particularly where tones either of high pitch or metallic quality are being reproduced, in which event reproduction is inclined to develop or exaggerate metallic sound as a result either of the inability of the diaphragmatic material to vibrate in harmony with the frequency of the transmitted tonal wave, or by reason of the metallic resonance of the material from which the diaphragm itself is formed. In accordance with the invention 10 it has been found by experiment that when a thin celluloid sheet for use as a diaphragm is immersed in a dilute solution of hydrochloric acid for a suitable period of time it undergoes a change producing a diaphragm 15 having a more natural reproduction of sound. For example a circular diaphragm of uniform thickness corresponding to a ratio of .007:1 to its diameter, concentrically embossed and provided with radial ribs for 20 strengthening purposes, was immersed in a dilute solution of hydrochloric acid composed of one part of hydrochloric acid to eight parts of water. The diaphragm was subjected to the action of the solution for a 25 period of approximately twenty hours and the resulting article gave a much better and more natural reproduction of sound particularly where tones of high pitch were concerned and in addition effectively eliminated 30 the undesirable metallic resonance found in known diaphragms.

Referring to the drawings; Figure 1 is a side elevation of a diaphragm embodying the invention. Figure 2 is an end view thereof. 45 Figure 3 is a cross sectional view taken on the line 3-3 of Figure 1.

Like numerals of reference indicate corresponding parts in each figure of the drawings.

50 In the drawings, the diaphragm 1 is constructed of a single piece of celluloid of a uniform thickness, such, preferably, corresponding to a ratio of .007:1 to its diameter. It has been found in practice that this ratio 55 between the thickness of the material and its diameter results in better sound reproduc-

tion as a diaphragm of such proportionate density has proven to be particularly sensitive to sound waves of varying frequency.

This diaphragm is concentrically embossed, as at 2, to provide a cup-shaped protuberance on one side and radially extending from the same are four ribs, as at 3, such ribs being formed by embossing or being struck up as customary to procure this result. These ribs or veins are preferably spaced an equal distance apart and terminate short of the periphery. Centrally of the protuberance 2 is an aperture 4 for the purpose of connecting to the stylus bar of the reproducer.

The diaphragm at any stage in its course of manufacture is totally immersed in a solution composed of one part hydrochloric acid to eight parts of water for a period of approximately twenty hours. Said celluloid diaphragm 1 is maintained in the hydrochloric acid solution for a period of approximately twenty hours and although no apparent physical or chemical change takes place during the prolonged immersion there is a distinct tonal difference in the diaphragm's reproduction when same is compared with others which have not been treated by the process, although we are unable to advance a chemical or technical theory for the results obtained by this process.

In the use of celluloid for such a diaphragm it has been found that this material is rendered more responsive when the process hereinbefore recounted is undergone; whereas the ribbing or embossing of the diaphragm further adds to its usefulness by strengthening the same.

What we claim is:

1. The process of treating a celluloid diaphragm, which consists in immersing it in a dilute solution of hydrochloric acid.
2. The process of treating a celluloid diaphragm, which consists in immersing it in a solution of one part of hydrochloric acid to eight parts of water.
3. The process of treating a celluloid diaphragm, which consists in immersing it for a period of twenty hours in a solution of one part of hydrochloric acid to eight parts of water.

Signed at the city of Toronto, Canada, this 14th day of March 1925.
GEORGE WALTER MASTERSON.
WILLIAM HARRY LLOYD.
